DRAWING TABLE OR THE LIKE

Filed Sept. 12, 1952

FIG. 1

FIG. 2

INVENTOR.

Thomas M. Rainey

UNITED STATES PATENT OFFICE

171,103

DRAWING TABLE OR THE LIKE

Thomas M. Rainey, Cleveland, Ohio

Application September 12, 1952, Serial No. 21,435

Term of patent 14 years

(Cl. D33—14)

To all whom it may concern:

Be it known that I, Thomas M. Rainey, a citizen of the United States, residing at Cleveland, State of Ohio, have invented a new, original, and ornamental Design for a Drawing Table or the like, of which the following is a specification, reference being had to the accompanying drawing, forming a part hereof, and in which:

Fig. 1 is a front perspective view of a drawing table or the like showing my new design; and

Fig. 2 is a rear perspective view thereof.

I claim:

The ornamental design for a drawing table or the like, as shown.

THOMAS M. RAINY.
